Patented Dec. 30, 1975

238,238

HANDLE FOR A HOSTESS TRAY OR THE LIKE

Manuel S. Ziskin, Mayfield Heights, and Harold O. Wagner Sheffield Lake, Ohio, assignors to American Trading & Production Corporation, Baltimore, Md.

Filed July 11, 1974, Ser. No. 487,600

Term of patent 14 years

Int. Cl. D8—06

U.S. Cl. D7—39

Fig. 1

Fig. 2

Fig. 3

FIG. 1 is a top plan view of a handle for a hostess tray or the like showing our new design;

FIG. 2 is a front elevational view; and

FIG. 3 is a side elevational view thereof.

The rear elevational view and opposite side elevational view respectively are identical to those shown in FIGS. 2 and 3.

We claim:

The ornamental design for a handle for a hostess tray or the like, substantially as shown and described.
